(57) **CLAIM**

The ornamental design for a belt clip, as shown and described.

DESCRIPTION

FIG. 1 is a perspective view of a belt clip showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

In the drawings, the broken lines depict environmental subject matter only and form no part of the claim.

1 Claim, 6 Drawing Sheets
